D. PARKS

METHOD OF UNITING A RUBBER HEEL AND LEATHER BASE

Filed Jan. 31, 1924

INVENTOR:
DENNIS PARKS

BY Bruce A. Elliott
ATTORNEY

UNITED STATES PATENT OFFICE.

DENNIS PARKS, OF ST. LOUIS, MISSOURI.

METHOD OF UNITING A RUBBER HEEL AND LEATHER BASE.

Application filed January 31, 1924. Serial No. 689,789.

To all whom it may concern:

Be it known that I, DENNIS PARKS, a citizen of the United States, residing in the city of St. Louis and State of Missouri, have invented new and useful Improvements in Methods of Uniting a Rubber Heel and Leather Base, of which the following is a specification.

This invention relates to the art of heel building, and more particularly to that branch of this industry which consists in securing a rubber heel to a leather base.

In building a composite heel blank consisting of a leather base and rubber tread or heel, I follow the general plan of procedure utilized in so-called log building, in which the heel lifts, either whole or pieced, supplied with paste, are forced downward in a container having, in cross-section, the general shape of a heel blank, and which offers sufficient resistance to require considerable pressure to force the column downward, so that the lifts are maintained in column formation and under pressure for a sufficient length of time to allow the paste used in connecting the lifts together to set.

The process, as heretofore practiced by me, differs from that of straight log building, in that each heel blank is built as a unit. As applied to composite heels of leather and rubber, the rubber heel has been inserted in the container in a horizontal position, the leather base with paste applied placed on top of the rubber heel, and then a plunger operated to force the heel blank downward in the container. A standard rubber heel, as now constructed, has its breast side inclined rearwardly from the bottom or tread surface to the top. In the use of such rubber heels, it follows that when the leather base is applied thereto, the breast of the leather base will project slightly beyond the upper edge of the rubber heel, due to the incline of the breast referred to. This necessitates a breasting operation to make the breast side of the leather base coincide with that of the rubber heel. This is an extra operation, and it is desirable to avoid the same if possible in order to reduce the cost of manufacture.

To overcome this objection, I have con-

ceived the idea of inserting the rubber heels in the container in an inclined position, that is, with the breast side of the rubber heel lower than the back or rounded side, so as 55 to bring the breast side of the rubber heel substantially parallel with the breast wall of the container. This, of course, results in positioning the upper edge of the breast of the rubber heel nearer to the breast wall of 60 the container than would be the case when the rubber heel occupies a horizontal position. The leather base is likewise inserted in a container and positioned on top of the rubber heel in a similar inclined position, 65 with the result that the lower edge of its breast is thrown inward. The degree of inclination is regulated, so that when the leather base is placed in position on the rubber heel, the lower edge of the breast of the 70 leather base will be flush with the upper edge of the breast of the rubber heel. In this way, I obviate the necessity of breasting the leather base to cause it to be flush with the breast of the rubber heel. 75

While this operation necessarily resides in forcing the rear or rounded side of the leather base beyond the corresponding side of the rubber heel, this is not an objection, as this occurs normally when the rubber heel and leather base are inserted in a horizontal position in the container, and the rounded side or back of the leather base must, therefore, be trimmed off in any event. Thus, no extra operation is involved, and 80 85 the breasting operation, as stated, is avoided.

The desired incline to the rubber heel and leather base is produced by employing a plunger having its operative face, or that 90 coming in contact with the upper surface of the leather base, inclined to the required degree, so that when it is lowered to force the heel blank into the container, the initial heel blank will be given the desired inclination, 95 and thereafter, as each rubber heel and leather base is inserted in the container on top of a preceding heel blank, it will rest in the container at such inclined position, and the plunger will then simply operate 100 to force the composite heel blank downward in the container. Of course, the pressure of

the plunger and the resistance offered to the movement of the heel blanks by the container will insure that each heel blank will be forced to exactly the same inclination by 5 the incline of the plunger, even though they only approximated such position when inserted by hand in the container.

In order that my invention may be clearly understood, I have illustrated diagrammatically in the accompanying drawing the relative positions of the leather base and rubber heel at the breast when the same are assembled in horizontal position in the container, and the change effected in their relative position by causing the parts to be given an inclined position.

Figure 1 shows, diagrammatically, the upper portion of a container with a composite heel blank therein in a horizontal position, and showing the off-set at the breast of the heel blank caused by the projection of the leather base beyond the upper edge of the breast of the rubber heel; and

Figure 2 shows, diagrammatically, the same parts as illustrated in Figure 1, but with the plunger having an inclined face or bottom, and composite heel blanks forced to an inclined position therein by the plunger, with the lower edge of the breast of the leather base flush with the upper edge of the breast of the rubber heel.

In Figure 1, the numeral 1 indicates a container, 2, a rubber heel inserted therein, 35 and 3, a leather base placed on top of the rubber heel with the interposition of paste. The numeral 4 indicates a plunger for forcing the leather base and rubber heel downward in the container.

40 The standard rubber heel employed has its breast 5 inclined rearwardly, as shown, with the result that the leather base forms an off-set or projection at the breast of the composite heel blank, as indicated at 6. If 45 assembled in the manner shown in Figure 1, this off-set must be cut off by the process of breasting before the heel blank can be secured to the shoe.

In Figure 2, the plunger 7 is provided 50 with an inclined bottom 8, and when the rubber heel and leather base are inserted in the container, and the plunger lowered, the heel blank will be caused to assume the inclined position shown, bringing the lower 55 edge of the breast of the leather base flush with the upper edge of the breast of the rubber heel, as indicated at 9. Thereafter, as each rubber heel and leather base are inserted in the container, they will assume a 60 corresponding inclined position and will be forced downward in the container at such incline, by reason of the inclined bottom 8 of the plunger 7. The plunger 8 will be adjusted to any desired incline according 65 to the incline of the breast of the rubber

heel employed, and for the sake of illustration, I have shown a conventional adjustable connection at 10.

I claim:

1. The method of uniting the members of 70 a composite heel-blank of leather and rubber, in which the breast of the rubber heel inclines rearwardly, which comprises pasting a leather base and a rubber heel together within a container, the walls of 75 which are engaged by the edges of said members while maintaining the members at such inclination as to bring the upper edge of the breast of the rubber heel substantially flush with the lower edge of the breast 80 of the leather base.

2. The method of uniting the members of 85 a composite heel-blank of leather and rubber, in which the breast of the rubber heel inclines rearwardly, which comprises pasting a leather base and a rubber heel together within a container, the walls of which are engaged by the edges of said members, and exerting pressure on the heel-blank while maintaining the same at such 90 inclination as to bring the upper edge of the breast of the rubber heel substantially flush with the lower edge of the breast of the leather base.

3. The method of uniting the members of 95 a composite heel-blank of leather and rubber, in which the breast of the rubber heel inclines rearwardly and the breast of the leather base is perpendicular to the surface 100 to be pasted, which comprises pasting a leather base and a rubber heel together within a container, the walls of which are engaged by the edges of said members and forcing them downward in a container 105 while maintaining the united parts at an inclination sufficient to substantially true the breast of the rubber heel with the wall of the container.

4. The method of uniting the members 110 of a composite heel-blank of leather and rubber, in which the breast of the rubber heel inclines rearwardly and the breast of the leather base is perpendicular to the surface to be pasted, which comprises pasting 115 a leather base and a rubber heel together within a container, the walls of which are engaged by the edges of said members and forcing them downward in a container by the use of a pressure member having its operative face inclined to such a 120 degree as to force the heel-blank to a position in which the breast of the rubber heel will be substantially parallel with the wall of the container.

5. The method of forming composite 125 heel-blanks of leather and rubber, in which the breast of the rubber heel employed inclines rearwardly and the breast of the leather base is perpendicular to the surface to be pasted, which comprises pasting a 130

leather base and a rubber heel together in a container the walls of which are engaged by the edges of said members while maintaining the united parts at an inclination sufficient to bring the upper edge of the breast of the rubber heel substantially flush with the lower edge of the breast of the leather base, and successively forcing heel-

blanks, as thus formed, downward in the container by the use of a pressure member 10 having its operative face inclined to the degree required to true the meeting breast edges of the rubber heel and leather base.

In testimony whereof I have hereunto set my hand.

DENNIS PARKS.
